Primary Examiner — Sandra Morris(74) *Attorney, Agent, or Firm* — Fredrikson & Byron, P.A.(57) **CLAIM**

I claim the ornamental design for a bottle, as shown and described.

DESCRIPTION

FIG. 1 is a perspective view of my new design for a bottle;
 FIG. 2 is a front view thereof;
 FIG. 3 is a side view thereof;
 FIG. 4 is a rear view thereof;
 FIG. 5 is an opposite side view thereof;
 FIG. 6 is a top view thereof; and,
 FIG. 7 is a bottom view thereof.
 The broken lines form no part of the claimed design.
